UNITED STATES PATENT OFFICE.

WALTER F. LAWRENCE, OF MIDDLETOWN, OHIO, ASSIGNOR TO RAYMOND BAG COMPANY, OF MIDDLETOWN, OHIO, A CORPORATION OF OHIO.

SHOPPING-BAG.

1,379,829.

Specification of Letters Patent.

Patented May 31, 1921.

Application filed July 1, 1920. Serial No. 393,383.

To all whom it may concern:

Be it known that I, WALTER F. LAWRENCE, a citizen of the United States, residing at Middletown, in the county of Butler and 5 State of Ohio, have invented a certain new and useful Improvement in Shopping-Bags, of which the following is a full, clear, concise, and exact description, reference being had to the accompanying drawings, forming 10 a part of this specification.

My invention contemplates the provision of a paper shopping bag and the principal objects of the invention are to provide an article of this class that can be economically 15 manufactured, that is neat in its appearance, and which comprises an improved arrangement for attaching the handles to the bag proper.

Heretofore the usefulness of paper shopping bags has been greatly limited because 20 of the tendency of the handles to tear out of or away from the paper bag body when called upon to sustain any considerable weight. I find that the improvements of my 25 present invention eliminate this difficulty. The bag of my invention, even when heavily laden, is no more apt to become disrupted at the handles or in the vicinity of the handles than it is apt to become disrupted at any 30 other point.

In the accompanying drawings, Figure 1 is a perspective of the shopping bag of my invention;

Fig. 2 is a fragmentary elevational view 35 of the portion of the bag to which one of the handles is applied, a portion of the inturned flap being broken away; and

Fig. 3 is a fragmentary section taken on line 3—3 of Fig. 2.

40 At 4 is illustrated a paper bag of any sufficiently strong and heavy paper, the upper edges of the bag being folded inwardly as indicated at 5. The bag handles 6—6 which are of heavy cord enter the bag 45 through the two pairs of spaced apertures 7—7, the ends of the handles terminating within the bag. As will presently appear, no strain is placed upon the paper bounding these apertures, it being the sole purpose of 50 the apertures to permit the ends of the cord handles to be concealed, as illustrated.

Disposed under the inwardly folded flap 5 of the bag are the oppositely disposed cardboard strips 8—8. At each of its ends, each 55 cardboard strip is provided with a section

of strong woven fibrous material, indicated at 9. The woven sections 9 are conveniently of coarsely woven buckram and are glued to the strips 8—8 on the surfaces thereof nearest the inturned flap 5. The cord handles are 60 attached to the bag and to the cardboard strips 8—8, and the latter are held in position under flap 5 by the staples 10—10. Each staple embraces a portion of a cord handle lying outside of the bag and passes 65 through the outer layer of paper, the adjacent cardboard strip 8 and its buckram section 9, and through the inturned flap 5. The extremities of the staples are turned over as indicated in Fig. 2 to lock together the 70 several parts through which they pass. The staples are conveniently widened at the points where they engage the cord, so that they may appear as buttons and at the same time minimize the wear on the cord which 75 is occasioned by the contact of the cord with the staples. The herein described arrangement for attaching the handles 6—6 to the paper bag 5 has been found to be very effective, since the staple legs pass between the 80 woven fibers of the buckram and hook therearound and since the buckram sections lie on the inner surfaces of the cardboard strips, there is no possibility that any carried article insufficient to disrupt the bag itself will 85 cause the staples to be torn out of the cardboard. Lifting strain imparted to the paper of the bag when the same and its contents are carried by the handles is evenly distributed over a substantial area, no isolated 90 portion of the bag being subjected by the handles to an excessive strain liable to tear the same.

Having thus described my invention, what I claim as new and desire to secure by 95 United States Letters Patent, is:

1. In combination with a paper bag folded at its upper edge to provide an inturned flap, two oppositely located spaced pairs of apertures in the bag, cord handles the ends 100 of which pass through said apertures and terminate within the bag, cardboard strips lying under said flap and provided on the surfaces thereof next adjacent said flap with sections of woven fibrous material, together 105 with staples embracing those portions of the cord handles which lie outside of the bag, said staples extending through the paper of the bag and through the cardboard strips and the woven material carried thereby, the 110

extremities of the staples being off set so that the staples can not be withdrawn from the cardboard without drawing the woven material through the cardboard.

- 5 2. In combination with a paper bag folded at its upper end to provide an inturned flap, a cardboard strip lying under said flap, said cardboard strip provided at each end thereof with a section of woven fibrous material lying on that side of the cardboard strip next adjacent said flap, a flexible handle having portions lying outside of and against the bag, and staples embracing said portions of the handle and passing through
- 10 15 the paper of the bag and through said cardboard strip and the woven fibrous material aforesaid.
3. In combination with a paper bag, a

cardboard strip disposed against the bag paper at its upper margin, a flexible handle 20 having portions lying against the bag at points adjacent said cardboard strip, staples embracing the said portions of the handle and passing through the bag paper and through said cardboard strip, said cardboard 25 strip provided with sections of woven fibrous material through which the legs of the staples pass and over which the staple extremities are clenched.

In witness whereof, I hereunto subscribe my name this 14th day of June, 1920.

WALTER F. LAWRENCE.
